UNITED STATES PATENT OFFICE.

JAMES E. SEELEY, OF LOS ANGELES, CALIFORNIA, ASSIGNOR TO HIGH FREQUENCY IGNITION COIL COMPANY, OF LOS ANGELES, CALIFORNIA, A CORPORATION OF CALIFORNIA.

SPARKING DEVICE FOR GAS-ENGINES AND THE LIKE.

1,086,565.

Specification of Letters Patent.

Patented Feb. 10, 1914.

Application filed July 12, 1905. Serial No. 269,319.

To all whom it may concern:

Be it known that I, JAMES E. SEELEY, a citizen of the United States, residing at Los Angeles, in the county of Los Angeles and State of California, have invented a new and useful Sparking Device for Gas-Engines and the like, of which the following is a specification.

The main object of this invention is to increase the power and effectiveness of the ignition spark that can be generated by a given battery or electromotive source.

A further object of the invention is to dispense with the use of any vibrator or other mechanical means other than the timing circuit controller.

Another object of the invention is to provide for the production of a spark wherein the energy of discharge will be developed and expended rapidly, thereby producing maximum temperature and igniting effect.

With ordinary sparking devices the spark may fail to pass at the gap, by reason of deposits on the gap, or if it passes it may expend its energy in a slow, weak discharge, insufficient to cause effective ignition.

My invention provides for production of a quick spark, applying high temperature suddenly to the motor, by the action of a high frequency discharge. Such a discharge is not affected by defective condition of the terminals, and it enables ignition to be effected with minimum expenditure of energy.

The accompanying drawing is a diagram of the apparatus, showing the circuit connections for the production of a secondary spark in the combustion chamber.

Referring to the figure, the invention is shown applied to two cylinders 1 of an explosive engine, said engine operating circuit controlling means comprising fixed, insulated contacts 2, and movable contacts 3, on arbors 4, operated by the engine through mechanism indicated at 30. The contacts 3 would generally be grounded. Each cylinder 1 is provided with an insulated electrode 26 adjacent to a projection 27 of the cylinder to form a spark gap in the combustion chamber of the engine.

50 The circuit controlling means 2, 3, is included in the discharge circuit 5, 6, of a condenser 7, and is also included in a charging circuit energized by a battery 10, and including a self induction means 11, having

a core 15 of magnetic material, the condenser 7 being connected across this charging circuit, so as to receive the self induction discharge from the self induction means 11. The discharge circuit 5, 6, also includes the primary coil 8 of a high frequency induction means or resonator whose secondary coil 24 is connected by wire 25 to the insulated electrode 26 in the combustion chamber. The inductance of coil 8 is small compared to that of coil 11, said coil 8 being of relatively few turns and having no magnetizable core.

The circuit connections are as follows: From battery 10 wire 12 leads to self-induction means 11, whence wire 13 leads to core 70 side of condenser 7, the other side of which is connected by wire 14 to the other side of battery 10. One side of condenser 7 is connected by wire 5 to "ground" on the engine frame and each contact 2 of the circuit 75 controller is connected by a wire 6 through one of the primary coils 8 to the other side of the condenser. Battery 10 is in uninterrupted connection with the condenser, but the charge of the condenser due to the electromotive force of said battery, solely, is negligible. When the circuit controller 2, 3, closes, current passes from battery 10 through wire 12, self-induction coil 11, wire 13, to one side of condenser, thence by wire 85 5 to contacts 3, 2, wire 6, through a primary coil 8 to the other side of the condenser, thence by wire 14, back to battery 10. This current energizes self-induction coil 11, and as long as the contacts 2, 3, remain in contact, this condition is maintained and there is no effective charging of the condenser. But when contact 3 leaves contact 2, this circuit is broken and the self induction coil 11 deenergizes, sending a self inductive discharge through said circuit and raising the portions of the circuit on opposite sides of the coil to a high potential difference, and as the condenser is connected to parts of circuit on opposite sides of said coil, it receives 95 a correspondingly intense charge, the self induction of the coil 11 being sufficient to store and release enough energy, even from a battery of small power, to effectively charge the condenser. This circuit also includes the primary coil 8, but the inductance of said coil is small compared to that of coil 11, and the condenser charge may be 100 105

considered as due substantially to coil 11 alone. As soon as the condenser has been charged to a certain extent it begins to discharge, this discharge taking place through 5 the circuit 5, 2, 3, 6, 8, the impedance of this circuit being so small that the discharge therein from the condenser is oscillatory and of high frequency. This discharge circuit is independent of the electromotive source or 10 battery so that the impedance is reduced to a minimum. The inductance of coil 11 is so great that this oscillatory discharge from the condenser cannot pass through the circuit 13, 11, 12, 10, 14, in appreciable quantity, and the energy of the discharge is concentrated in the circuit including coil 8. This induces in coil 24 a high frequency oscillatory discharge, which by wires 25, 6 is applied to the sparking electrode. Owing 20 to the small impedance of the discharge circuit, this oscillatory discharge is of high frequency as well as of high tension; it is for this reason not affected or interfered with by defective insulation of the spark 25 gap, and by reason of the small impedance of the circuit, the time of growth and dying away of the discharge is reduced to a minimum, giving a short spark that applies the energy from the condenser with maximum 30 suddenness to the explosive mixture.

It will be noted that the invention comprises a charging circuit including a battery and inductance means, and a circuit controller, a condenser connected to the 35 charging circuit, to be charged by the discharge from the inductance means, with a discharge circuit for the condenser, including an inductance and a spark gap. This spark gap may be in the combustion chamber 40 of the engine, or the discharge circuit may, through a secondary circuit, control another spark gap, which is in the combustion chamber, but in either case the discharge must be of high frequency and the inductance in the 45 discharge circuit must therefore, be of small amount, whereas the charging inductance 11 must be of considerable magnitude.

It is characteristic of the invention that the high frequency induction coil or resonator 50 8, 24 is of extremely low impedance and has a magnetic circuit of low permeability and hysteresis as compared with the ordinary iron-containing magnetic circuit, so as to present maximum frequency. It is further characteristic of the resonator that it is 55 adapted to produce a high frequency discharge whose energy is delivered substantially at one terminal only, the potential at the one terminal being much greater than at the other. Thus in the form shown, where the resonator is in the form of a disk or flat spiral having the primary connections respectively at the outside and at the part of the winding near the outside and the effective 60 secondary connections from the center 65

of the coil, the potential is presented substantially solely at the inner terminal or at the wire 25 connected thereto. The importance of this property of the resonator lies in the fact that when high frequency discharge is 70 grounded at one side, for example, to the body of the engine, the energy of the discharge at that point is dissipated in the ground or in the body of metal, but by concentrating the energy of the discharge at one 75 terminal and making this terminal the discharge terminal of the spark gap the energy is dissipated wholly in the spark gap, aside from the losses in the intervening circuit. In order to produce this concentration of 80 the discharge at one terminal, it is essential that the secondary should be of such form that one end thereof is considerably nearer the primary winding than the other end. This is accomplished by making the coil in 85 disk or spiral form, the number of layers being considerable relatively to the number of turns in each layer, so that the inner layers are comparatively remote from the outer primary winding and the outer layers 90 of said secondary are comparatively close to said primary winding. With such a construction of coil and the proper adjustment of inductance and capacity in the circuit, so as to produce resonance, the maximum induction and maximum variation of current will occur in the outer turns of the secondary, and the maximum variation of electro-motive force will occur at the inner end of 95 said secondary. 100

What I claim is:

1. The combination with a combustion chamber of an explosion engine, of sparking means therefor comprising spark gap means with fixed electrodes, in the combustion chamber, a condenser, a discharge circuit therefor, a resonator having its primary included in the discharge circuit of the condenser and its secondary connected to said spark gap, and a charging circuit for the condenser, including a battery, a self-induction coil, and a circuit controller, said discharge circuit of the condenser being independent of the electromotive source, the said circuit controller being operated to close the circuit and to open the circuit when the spark is required and being so connected that, when the circuit is closed thereby, the battery charges the self-induction coil, and when the circuit is opened by said circuit controller, a gap is formed therein, the condenser then being charged by the action of the coil and immediately discharging itself through the said gap and the primary of the said resonator, thus producing a spark at the 115 electrodes when the charging circuit of the condenser is broken. 120

2. The combination with a combustion chamber of an explosion engine, of sparking means therefor comprising spark gap means 130

with fixed electrodes in the combustion chamber, a condenser, a discharge circuit therefor, a resonator having its primary included in the discharge circuit of the condenser and its secondary connected to said spark gap, and a charging circuit for the condenser, including an electromotive source, a self-induction means, and a circuit controller, the discharge circuit for the condenser being of relatively low inductance and being independent of the electromotive source and the charging circuit being of relatively high inductance, said circuit controller being connected to be operated by the engine to close the circuit to energize the self-induction means and immediately thereafter to open the circuit to cause the discharge from the self-induction means to charge the condenser and to permit the condenser to then immediately discharge through the said discharge circuit therefor, including the break at the circuit controller as a primary spark gap.

3. The combination with a combustion chamber, of an explosion engine, of sparking means therefor comprising spark gap means with fixed electrodes in the combustion chamber, a condenser, a discharge circuit therefor, a resonator having its primary included in the discharge circuit of the condenser and its secondary connected to said spark gap, and a charging circuit for the condenser, including an electromotive source, a self induction coil, and a circuit controller, the said discharge circuit of the condenser being independent of the self-induction coil, said circuit controller being connected to be operated by the engine to close the circuit controller and immediately thereafter open the same at the time a spark is required for the operation of the engine, whereby the self-induction coil is energized on such closure of the circuit controller and on opening of the circuit controller said self-induction coil charges the condenser and immediately thereafter the condenser discharges through its said discharge circuit including the break at the circuit controller as a primary spark gap, the spark gap means with fixed electrodes in the combustion chamber having relatively fixed electrodes to maintain sparking relation during the said discharging operation.

4. The combination with a combustion chamber of an explosion engine, of sparking means therefor comprising spark gap means with fixed electrodes in the combustion chamber, a condenser, a discharge circuit therefor, a resonator having its primary included in the discharge circuit of the condenser and its secondary connected to said spark gap, and a charging circuit for the condenser, including an electromotive source, a self-induction coil, and a circuit controller, said discharge circuit of the condenser be-

ing independent of the electromotive source, said circuit controller being connected to be operated by the engine to close the circuit to energize the induction coil and immediately thereafter to open the circuit to cause the discharge from the self-induction coil to charge the condenser and to permit the condenser to then immediately discharge through the said discharge circuit therefor, including the break at the circuit controller as a primary spark gap, the secondary coil of the resonator having one end farther removed than the other end thereof from the primary winding of the resonator whereby high frequency electromotive force becomes effective substantially wholly at one end of the secondary coil of the resonator, and the spark gap means being connected to said end of the resonator which is of higher potential.

5. The combination with a combustion chamber of an explosion engine, of sparking means therefor comprising spark gap means with fixed electrodes in the combustion chamber, a condenser, a discharge circuit therefor, a resonator having its primary included in the discharge circuit of the condenser and its secondary connected to said spark gap, and a charging circuit for the condenser, including an electromotive source, a self-induction coil, and a circuit controller, said discharge circuit of the condenser being independent of the electromotive source, said circuit controller being connected to be operated by the engine to close the circuit to energize the induction coil and immediately thereafter to open the circuit to cause the discharge from the self-induction coil to charge the condenser and to permit the condenser to then immediately discharge through the said discharge circuit therefor, including the break at the circuit controller as a primary spark gap, the secondary coil of the resonator having one end farther removed than the other end thereof from the primary winding of the resonator whereby high frequency electromotive force becomes effective substantially wholly at one end of the secondary coil of the resonator, and the spark gap means being connected to said end of the resonator which is of higher potential.

6. The combination with a combustion chamber of an explosion engine, of sparking means therefor comprising a spark gap with fixed electrodes in the combustion chamber, a condenser, a discharge circuit therefor, a disruptive discharge coil having its primary included in the discharge circuit of the condenser and its secondary connected to said spark gap, and a charging circuit for the condenser including an electromotive source and a circuit controller, the discharge circuit for the condenser having low inductance and being independent of the electromotive source, and the charging circuit having high inductance, said circuit controller being operated by the engine.

to first charge the condenser through the
said charging circuit and then to imme-
diately discharge the condenser through said
discharge circuit therefor, including the
5 break at the circuit controller as a primary
spark gap.

In testimony whereof, I have hereunto set

my hand at Los Angeles, Cal., this 3rd day
of July, 1905.

JAMES E. SEELEY.
